DIFFERENTIAL CONDENSER CIRCUITS

Hans Berthold, Berlin, Germany, assignor to C.
Lorenz Aktiengesellschaft, Berlin-Tempelhof,
Germany, a company

Application June 7, 1939, Serial No. 277,784
In Germany June 16, 1938

2 Claims. (Cl. 178—44)

This invention relates to differential condenser circuits, and more particularly to circuit arrangements in which one or more tuning or similar circuits are coupled to an oscillatory circuit which comprises a differential condenser adapted to perform amplitude or other regulation of the last mentioned circuit.

It is a well known fact in the art that severe difficulties are encountered in rendering a further circuit or circuits independent of the relative position of adjustment of the heretofore known differential condensers which for the purpose of effecting adjustment of any kind has been used in an oscillatory or other circuit with which the first mentioned circuit or circuits are coupled. These difficulties are due to the fact that the effective capacity of a circuit including a differential condenser strongly depends upon the position of the rotor plate thereof relative to the stator plates, and that a capacity change of the circuit in response to a position change of the movable plate with respect to the stationary plates simultaneously affects the other circuits in an undesired sense.

My invention has for an object to overcome the difficulties mentioned in the foregoing by so dimensioning a differential condenser forming part of an electric circuit that an angular adjustment of its rotor relative to the stator plates in order to effect amplitude regulation has no influence upon another circuit or circuits being coupled to the first mentioned electric circuit.

The invention will be more readily understood from the following description taken in conjunction with the accompanying drawing, in which:

Fig. 1 shows a known circuit arrangement explanatory of the art, Fig. 2 is an equivalent circuit of that shown in Fig. 1, Fig. 3 is a diagrammatic showing according to the present invention, Fig. 4 shows the configurations of the various plates or vanes of a differential condenser designed in accordance with this invention, while Fig. 5 schematically shows one embodiment to which my novel differential condenser is applied.

A circuit arrangement of conventional design is shown in Fig. 1, in which a tuned oscillatory circuit K_1 is coupled with a further electric circuit K_2 including a differential condenser D which, by way of an example, has for its object to regulate the voltage impressed upon the circuit K_2 from a voltage source G . The voltage regulating circuit K_2 comprises a voltage divider S , preferably in the shape of an inductance, the two outer terminals A and B of which are each

connected to one of the stationary plates a and b , respectively, of the differential condenser D . The voltage source or generator G , the capacitive impedance of which is represented by the reference C_s is applied to the circuit K_2 between the tapped mid-point M of the inductance S and the rotor L of the differential condenser D . The difficulties mentioned in the foregoing will be easily appreciated by taking the present conditions under consideration, since as a matter of fact the effective capacitance at the terminals A and B of the inductance coil depends upon the relative position of the rotor of a differential condenser heretofore employed in circuits of this kind. A change in capacity in response to an angular movement of the rotor plate relative to the stator plates for the purpose of amplitude regulation will be transferred to the oscillatory circuit K_1 which will become detuned.

According to the main feature of this invention, the differential condenser is so designed and dimensioned, that the effective capacity at each terminal of the voltage divider or inductance S connected therewith remains constant independent of the angular position of the rotor plate or vane to the stator plates thereof.

The total capacity across the voltage divider or inductance S in Fig. 1 will now be more closely considered in conjunction with the equivalent circuit of Fig. 2 which shows the individual component capacitances into which the total capacity may be decomposed. These component capacitances are partially constant and partially variable in response to an angular displacement 35 of the rotor plate relative to the stator plates as will hereinafter be fully explained. In Fig. 2, the reference C_2 represents the constant shunt capacity or initial capacity between the two stationary condenser plates a and b of Fig. 1 which 40 may be measured when the rotor plate L is removed. The constant capacity of the outer circuit, that is, across the rotor of the differential condenser and the tapped mid-point M between the terminals A and B of the inductance S indicated at C_s in Fig. 1 is likewise designated C_s in Fig. 2. The references C_a and C_b denote variable component capacitances between the rotor plate and the stator plates a and b , respectively, of Fig. 1, that is, the capacity measured between the 45 rotor and the respective stator plate minus the initial capacity.

The plates or vanes of the conventional differential condensers generally present such configuration that the sum of the variable capacitances, i. e. $C_a + C_b$ remains constant. The capacity be-

tween the rotor and the tapping point M is thus constant, but that between the terminals A and B is highly variable particularly at a low capacity C_s . The maximum value exists in the central position of the condenser when $C_s=0$ and $C_{AB}=2.5C_{a\max}$, while the minimum value is reached in the end position of the rotor, that is, when $C_s=0$ and $C_{AB}=C_0$.

Because of the fact that the impedances

$$\frac{1}{wC_a}$$

and

$$\frac{1}{wC_b}$$

respectively, are always larger than the impedance across the terminals A and B of the inductance S by bearing in mind the fulfilled condition of resonance, the capacitance across the terminals A and B, hereinafter referred to as C_{AB} may be defined as follows:

Let the voltage from A to B be equal to E. Assuming an ideal coil and coupling between turns, the voltage drop due to current in the coil will be negligible and the voltage across the condensers C_a and C_b will be equal to $\frac{1}{2}E$ since the coil is tapped at its mid-point. Accordingly the following mesh equations may be set up:

$$\frac{z}{wC_s} + \frac{z+y}{wC_b} = \frac{1}{2}E$$

$$\frac{x}{wC_0} = E$$

$$\frac{y}{wC_a} + \frac{z+y}{wC_b} = E$$

Solving for x, y, and z:

$$x = EwC_0$$

$$y = \frac{Ew}{2} \left(\frac{2C_aC_b + C_aC_s}{C_a + C_b + C_s} \right)$$

$$z = \frac{Ew}{2} \left(\frac{C_bC_s - C_aC_s}{C_a + C_b + C_s} \right)$$

The capacitive current from A to B is:

$$I_{AB} = x + y + \frac{1}{2}z$$

and

$$EwC_{AB} = I_{AB} = x + y + \frac{1}{2}z$$

then

$$C_{AB} = \frac{x + y + \frac{1}{2}z}{wE}$$

or

$$C_{AB} = C_0 + \frac{C_aC_b + \frac{1}{4}C_aC_s + \frac{1}{4}C_bC_s}{C_a + C_b + C_s}$$

Since this last expression shall remain constant in response to variations of C_a and C_b , it may be rewritten as follows:

$$\frac{C_aC_b + \frac{1}{4}C_aC_s + \frac{1}{4}C_bC_s}{C_a + C_b + C_s} = k$$

In the last expression, k is a constant, the magnitude of which is determined by the component capacitances in either of the outer positions of the rotor, e. g. when $C_b=0$ and $C_a=C_{\max}$, in which case:

$$k = \frac{C_{\max}C_s}{4(C_{\max} + C_s)}$$

In this formula, $C_{\max}$ represents the maximum values of the component capacitances C_a and C_b , respectively, that is, the nominal capacity of the condenser.

Now, the plates of a differential condenser capable of involving the maximum capacity $C_{\max}$, at a constant capacitance C_s of the outer circuit

between the rotor plate L and the tapping midpoint M of the inductance S in Fig. 1, without subjecting the inductance S as a whole to any capacitance changes in response to an angular displacement of the rotor plate relative to the stator plates must, according to one feature of this invention, be so dimensioned that the following relationship exists between the component capacitances C_a and C_b :

$$C_a = \frac{k \cdot C_s - C_b(0.25C_s - k)}{C_b + (0.25C_s - k)}$$

The ratio of C_a to C_b is diagrammatically shown in Fig. 3 in response to a given magnitude of the capacitance C_s . Such characteristic is secured in accordance with still another feature of this invention by the use of a semicircular rotor plate R, and stator plates S_1 and S_2 of fabricated configuration as shown in the Fig. 4.

The Fig. 5 schematically embodies a radio direction finding receiver in which a differential condenser according to this invention is applied in order to perform voltage regulation in the non-directional auxiliary antenna system thereof. In this embodiment reference letter H denotes the auxiliary antenna and RA the directional frame aerial coupled to the input tube E of a receiver over an oscillatory circuit K_g which corresponds to the circuit K_1 of Fig. 1, and a detuning of which shall be avoided. The differential condenser D designed and dimensioned in accordance with the rule disclosed by this invention is adapted to control the voltage of the auxiliary antenna H. Because of the fact that the capacitance between the points or terminals A and B remains constant independent of the relative position of the rotor plate to the stator plates of the differential condenser D, no detuning of the oscillatory circuit K_g will result from a regulation of the voltage of the auxiliary antenna H. In the case under consideration, the capacity of the auxiliary antenna H corresponds to the constant load capacity C_s above referred to.

What is claimed is:

1. An electric circuit arrangement comprising a voltage divider coil and a constant capacity circuit across the ends of said coil comprising a variable condenser comprising a semi-circular plate rotatable about an axis and a pair of stationary plates disposed on opposite sides of said axis and parallel with the plane of said rotatable plate and in capacity relation therewith, the adjacent edges of said stationary plates having a concave falcate shape, and a substantially fixed capacity connected between said rotatable plate and the center of said coil.

2. An electric circuit arrangement comprising a voltage divider coil and a constant capacity circuit across the ends of said coil comprising a variable condenser comprising a rotatable plate and a pair of stationary plates in capacity relation therewith, and a substantially fixed capacity connected between said rotatable plate and the center of said coil, said plates having shapes and relative positions determined by:

$$C_a = \frac{k \cdot C_s - C_b(0.25C_s - k)}{C_b + (0.25C_s - k)}$$

where C_a and C_b denote the variable capacities between said rotatable plate and said stationary plates, C_s denotes said fixed capacity, and k denotes a constant dependent upon said fixed capacity and the maximum capacity between said rotatable plate and one of said stationary plates.

HANS BERTHOLD.
